PULPING AND FINISHING MACHINE

Stacey B. Lindley, Indianapolis, Ind., assignor to
 Indiana Canning Machinery Company, Indianapolis, Ind., a corporation

Application March 13, 1937, Serial No. 130,643

4 Claims. (Cl. 146—174)

This invention relates to machines for pulping of tomatoes, pumpkin, vegetables and various fruits, and with slight modification is also applicable for finishing of the pulp therefrom.

5 One feature of the invention resides in the construction of the crusher having serrated edges on one side, which revolves at high speed. The crusher is mounted on the drive shaft in association with the receiving hopper of the machine at an angle for receiving and crushing the material and propelling it forward into the screen. The serrated edges have the advantage of masticating the material to be pulped, thus conditioning it for more ready pulping in the 10 screen.

Another feature of the invention resides in the provision of a unitary paddle assembly rotatable in the screen which may be readily removed through one end thereof longitudinally of the 15 screen as a unit.

Another feature of the machine resides in the adjustability of the paddles which are more effective when capable of adjustment in three ways due to changing conditions of the material or 20 various types of material to be pulped. These changes and adjustments should be quickly made without dismantling the machine, so as not to hold up the continuous production during the season. These adjustments include the clearance 25

30 of the paddles, the angular lead of the paddles and the speed of rotation. By means of this invention, the clearance of the paddles may be adjusted exteriorly of the screen by longitudinal adjustment of the shaft and unitary paddle assembly mounted thereon with respect to the screen while the machine is in operation. The screen as shown herein, being in the form of a truncated cone, longitudinal movement of the paddle unit will have the effect of increasing or 35

40 decreasing the clearance between the paddles and the screen. With respect to the adjustment of the angular lead of the paddles, wherein the front or intake ends thereof are set ahead of the rear or discharge ends, this is effected by having 45 one spider or set of paddle supporting arms rotatably adjustable with respect to the other set. Set screws are provided for effecting the rotary adjustment to vary the lead of the paddles, preferably at the discharge end of the machine 50 which is easily accessible.

Another feature of the machine resides in the provision of an angularly disposed flange along the edge of the paddles adjacent the screen, such as will produce a wedging action of the material being pulped. This action squeezes the material 55

and forces the pulp through the machine without cutting the fibres. To this end, it provides a dragging and squeezing action, as distinguished from a cutting and breaking action. This is most important as a thicker and more desirable appearing pulp is thereby obtained.

Other features of the invention reside in the truncated cone screen having its reduced end at the intake and its enlarged end at the discharge. This results in the material being moved toward the discharge end of the machine by the paddles, effecting more even distribution over all parts of the screen, so that the wear thereon will be more uniform. This has the effect of increasing the life of the screen and preventing excessive localized loads, tending to rupture it. The surrounding casing, with the associated discharge pan for the pulp and juice passing through the screen, comprises an integral casting conforming to the truncated cone shape of the screen 20 so that the screen may be readily inserted through the large end thereof without the necessity of providing divided sections, as in the usual construction. The enlarged end of the casing into which the screen is inserted is closed by a single end casting which includes the end thrust bearing for the shaft, as well as the discharge 25 spout for pomace.

The full nature of the invention will be understood from the accompanying drawing and the following description and claims.

Fig. 1 is a side elevation of the machine showing parts thereof in central vertical section. Fig. 2 is an elevation of the discharge end of the machine. Fig. 3 is a section of the drive shaft 35 with the longitudinal adjusting mechanism and bearing support being shown in central vertical section. Fig. 4 is a section taken on the line 4—4 of Fig. 1. Fig. 5 is a modified form showing the end of a portion of the machine with the intake end adapted to a finisher.

In the drawing there is illustrated a pulping and finishing machine having the usual frame support 10 in which there is provided a bearing support 11 through which the drive shaft 12 45 slidably and rotatably extends, carrying the drive pulleys 13 on the outer end thereof. Fixedly and permanently supported on the frame support 10 there is a solidly cast or otherwise formed unitary hood 14 having a body portion of truncated cone 50 shape and a bottom portion in the form of a discharge hopper 15. Said hood is thus formed to completely enclose the pulping section of the machine and being of solid or continuous construction prevents any leakage, and further has 55

the effect of keeping the outside air from having contact with the pulp that has passed through the perforated screen to be hereinafter described. The intake end of the machine comprises a casting including a packing gland portion 16 for the shaft 12 and an intake hopper 17. The discharge end of the machine is closed by an end casting 18 having a supporting bearing 19 and a discharge spout 20, said end casting being removably secured to the machine by the wing nuts 21.

Slidably and removably mounted in the machine there is a screen assembly which is of truncated cone shape to conform with the shape of the machine. Said assembly comprises a plurality of longitudinal supporting bars 22 secured to the annular reinforcement rings 23 for supporting the screen 24. Adjacent the forward end of the screen assembly and secured interiorly thereof there is an apertured partition 25. With the end casting 18 removed, the screen assembly may be readily inserted into the hood so that the forward end fits and seats upon a suitable retaining shoulder provided in the intake end casting.

25 The shaft 12 extends centrally within the hood and screen, being supported in the bearings 11 and 19. Adjacent the packing gland 16 and in the hopper 17 there is provided a feed screw section 26 which is immediately followed by a crusher 27 in the form of a two-bladed impeller provided with serrated edges 28. For adjusting the shaft 12 longitudinally of the machine, the bearing 11 is provided with an externally threaded sleeve 29 upon which an internally threaded collar 30 is adapted to screw which is provided with a hand wheel 31 (see Fig. 3). The collar 30 embraces a ball bearing assembly 32 having an inner race secured and locked to the shaft. The sleeve 29 is fixed to the frame of the machine through the bearing 11. The collar 30 is longitudinally fixed through the ball bearing assembly 32 to the shaft. Rotation of the hand wheel 31 causes longitudinal adjustment between the collar and sleeve and thereby effects corresponding longitudinal adjustment between the shaft and bearing 11.

With the end casting 18 removed and the screen assembly in place, the paddle assembly may be inserted within the screen and secured for rotation to the shaft 12. The paddle assembly comprises a longitudinally extending hub 33 which is keyed to the shaft at 34 and is provided at the reduced or intake end with a rigid spider formed of integral radially-extending arms 35. At the opposite or discharge end there is provided a similar spider comprising radially-extending arms 36, which, however, are rotatable independently of the hub 33. The paddles 37 are secured to the corresponding ends of the respective arms 35 and 36, the arms 36 being longer than the arms 35 so that the paddles are arranged in the general form of the screen. Through the screw adjustments 38 the paddles may be set to have the desired average or normal clearance between their outer edges and the inner surface of the screen. To adjust the lead or pitch of the paddles, the hub 33 is provided with a yoke at the discharge end, having four arms 39, as illustrated in Fig. 4, through which the adjusting screws 40 extend for engaging and clamping therebetween the projections 41 on the arms 36. By means of this adjustment and the setting of the screws 40 any relative rotational adjustment between the arms 36 and the arms 35 may be effected within limits. This permits of such ad-

justment of the rear spider as to affect the lead of the paddles, depending upon the character of the product being processed. This adjustment is readily accessible merely by removal of the nuts 21 and end casting 18.

As is illustrated in Fig. 4, the outer and effective edges of the paddles are provided with rearwardly extending flanges 42 extending outwardly at an angle to the tangent of the arc of rotation. Said flanges may have a straight surface as illustrated 10 or may be curved to the same substantial effect, to the end that the pulp may be wedged between the angular or sloping surface of the flange and the screen so as to be squeezed therebetween.

In the modified form shown in Fig. 5, the structure above described is the same, excepting that the intake end casting is changed and the apertured partition 25 is removed. The intake end casting of Fig. 5 is adapted for use on a finisher and comprises an intake 117 to which a pipe may be connected for introducing the pulp for the finishing operation, the pulp being directly discharged thereby into the screen section and distributed thereabout by a baffle plate 125 which is secured to and rotated by the shaft 12. 25

In assembly, the shaft and intake end casting form a permanent part of the structure, together with the frame 10 and the hood 14 with its pan 15. All of the other parts are removably mounted in connection therewith. The crusher 27 is 30 removably secured upon the shaft 12. Then the screen assembly is inserted about the shaft and within the hood. The screen has removably mounted therein for insertion the apertured plate 25. After mounting of the screen the paddle assembly is slipped on over the shaft to position for obtaining the approximate or normal clearance for the screen and thereupon locked to the shaft. The paddles are adjusted to give the desired lead, after which the end casting 18 is 40 locked in place by the wing nuts 21. In operation, depending upon the results obtained, the clearance of the paddles may be further adjusted by the hand wheel 31 while the mechanism is in operation, or their angular position may be further adjusted by removing the end casting 18 and adjusting the set screws 40. For dismantling and cleaning, the reverse operation would take place.

The material is received through the hopper 50 and broken up by the crusher 27, particularly through the medium of the serrated edge 28. Those parts which are small enough may then pass through the apertures in the plates 25, and those that are too large may remain to be further 55 broken up and crushed by the crusher. The truncated cone form of screen will thereupon cause the material to be evenly distributed throughout its length as it is being processed and crushed by the wedging action of the flanges 42 of the 60 paddles. The fibrous pulp and juice will be forced through the screen by the wedging action of the flanges 42 to pass into the discharge pan 15. Both the distribution of the material through the length of the screen and the final discharge of the 65 pomace through the spout 20 in the end casting 18 will be effected by the angular position of the paddles 37 adjusted to vary the speed of travel through the machine by the adjusting screws 40. The effect of the processing, mainly depending 70 upon the product desired and the character of the material used, is controlled through the clearance between the paddles and screen as adjusted by the hand wheel 31. The same applies to the finisher illustrated in Fig. 5, other than that there is no 75

crushing required and the paddles may be longer and the screen of finer mesh.

The invention claimed is:

1. A processing machine of the character described comprising a stationary screen of greater diameter at one end than the other in the form of a truncated cone, a shaft extending horizontally and axially through said screen, means for driving said shaft, a series of paddles having their outer edges extending substantially longitudinally of said screen and equally spaced therefrom, said paddles extending at an angle to said shaft and rotatable thereby with respect to said screen, a plurality of fixed bearings for slidably and rotatably supporting said shaft, a threaded sleeve secured to one of said bearings intermediate the ends of said shaft, an intermediate bearing longitudinally fixed to said shaft adjacent said sleeve, and a rotatable collar screw threaded on said sleeve and secured to said last-mentioned bearing for moving it and said shaft longitudinally upon rotation thereof while the machine is in operation.
2. A processing machine of the character described comprising an elongated screen circular in cross section, a shaft extending axially of said screen, means for rotating said shaft, a plurality of crushing paddles mounted upon and rotated by said shaft and extending longitudinally of said screen in crushing relation therewith, a set of radial arms having their outer ends secured to said paddles adjacent one end thereof and a set of corresponding arms spaced therefrom and secured to said paddles adjacent their opposite ends, a hub surrounding and secured to said shaft connected with one set of arms and extending to the other set of arms, and means on said hub for adjustably connecting said last-mentioned arms
3. A processing machine of the character described comprising an elongated screen circular in cross section, a shaft extending axially of said screen, means for rotating said shaft, a plurality of crushing paddles mounted upon and rotated by said shaft and extending longitudinally of said screen in crushing relation therewith, a pair of spaced supports for said paddles secured thereto adjacent their opposite ends, a hub secured to said shaft intermediate said supports having one end secured to one of said supports, and adjustable means on the other end of said hub for securing the other support in angular adjusted position to the first support.
4. A processing machine of the character described comprising a stationary screen annular in cross section and of greater diameter at one end than the other in the form of a truncated cone, a shaft extending axially through said screen, means for driving said shaft, a series of paddles having inwardly and rearwardly extending flanges formed on their outer edges adjacent said screen and equally spaced therefrom, means for adjusting said shaft and paddles longitudinally of said screen for varying the clearance of said paddles while the machine is in operation, means for adjusting the angular position of said paddles with respect to a plane through said shaft, a rigid shell surrounding said screen and conforming in shape thereto, a rigid end piece removably secured to one end of said shell for providing an end thrust bearing for said shaft, an intake end piece secured to the opposite end of said shell, and a toothed crusher member mounted on said shaft between said intake end piece and paddles.
